UNITED STATES PATENT OFFICE

165,474

CLOCKCASE OR SIMILAR ARTICLE

Abraham Levy, Brooklyn, N. Y., assignor to
United Metal Goods Manufacturing Co., Inc.,
Brooklyn, N. Y., a corporation of New York

Application February 9, 1951, Serial No. 14,155

Term of patent 14 years

(Cl. D42—7)

To all whom it may concern:

Be it known that I, Abraham Levy, a citizen of the United States of America, residing in Brooklyn, Kings County, New York, whose post-office address is 1/2 United Metal Goods Manufacturing Co., Inc., 379 De Kalb Avenue, Brooklyn (5), New York, have invented a new, original, and ornamental Design for a Clockcase or Similar Article, of which the following is a specification, reference being had to the accompanying drawing, forming a part hereof.

Figs. 1 and 2 are perspective views of the clockcase or similar article of the present invention, taken from the right and left respectively, of the article.

Fig. 3 is a front elevation and Fig. 4 is a side elevation of the same.

Fig. 5 is a perspective view of a portion of the clock, as appearing in a section taken on line 5—5 of Fig. 3.

A characteristic feature of the clockcase or similar article is a pair of diagonally set side mirrors, as shown in Fig. 5.

I claim:

The ornamental design for a clockcase or similar article, as shown and described.

ABRAHAM LEVY.
